UNITED STATES PATENT OFFICE.

ARTHUR TREVE HOLMAN, OF CAMBORNE, AND KENNETH JAMES HOLMAN, OF CARBIS BAY, ENGLAND, ASSIGNEES TO HOLMAN BROTHERS LIMITED, OF CAMBORNE, ENGLAND, A BRITISH COMPANY.

FORGING MACHINE.

Application filed April 4, 1925, Serial No. 20,714, and in Great Britain January 13, 1925.

This invention relates to forging machines, and particularly to an improved valve mechanism for sequentially operating the work holding and forging mechanisms.

5 The invention is herein described and shown as applied to the type of forging machine shown in British specification No. 5452/1924.

In machines of the type to which the present invention relates a pair of jaws or 10 other work-holding members is provided, one of which jaws or members is movable by means of a piston-and-cylinder device towards the other. The jaws are adapted to hold between them the drill bit or the 15 like while a reciprocating dolly or forging hammer operates on the end face of the bit or the like.

With such jaws there is also generally and preferably associated a part which 20 serves to forge or shape portions of the drill bit before end sharpening or shaping is effected by the dolly.

The forging machine to which the present invention is shown herein as applied comprises the combination of a movable jaw 25 with two pistons and cylinders arranged in tandem, the pistons being both carried on a single piston rod and serving jointly, when the dolly is to be used, to actuate the movable jaw to close it on to or towards the companion jaw.

According to the present invention in or 30 for a forging machine having the characteristic features above referred to, control means is provided for supplying driving fluid at will either—

(a) To one cylinder alone (for example the upper cylinder);
40 (b) To both cylinders simultaneously; or
(c) To both cylinders and to the cylinder of the dolly hammer simultaneously.

When the two pistons above referred to are associated with a third piston and cylinder constituting the means for returning the 45 movable jaw to the open position, the present invention further comprises the combination of a chamber to which driving fluid is supplied, a conduit which is always in open communication therewith and with the cylinder of the third or return piston, and another conduit which is open at one 50 end to the said chamber and at the other end leads to the control means above stated.

Preferably the chamber to which driving

fluid is supplied is provided by a pedestal 55 or support for the machine.

In order that the invention may be more clearly understood, one preferred construction will now be described with reference to the accompanying drawing which illustrates a central sectional elevation of the machine in a plane transverse to that containing the axis of the dolly hammer.

The machine now illustrated is similar to that described and illustrated in our co-pending United States patent application, Serial No. 710,326, filed May 1, 1924, and has a pedestal or support 10 for three cylinders 11, 12 and 32 in which work respectively three pistons 13, 14 and 31. The three 70 pistons are all mounted on a single piston rod 15. The two pistons 13 and 14 serve when required jointly to move the movable jaw, which is formed on or applied to the lower face of the upper piston 14, towards 75 the fixed jaw constituted by or mounted in the head of the cylinder 11. The piston 31 serves as a return piston for opening the movable jaw.

These parts have been given the same 80 reference numerals as were given in the prior specification and are in all their essentials similar in construction to those previously described.

The control means for the air supply 85 to the several cylinders is in the present invention as follows:—The pedestal 10 is formed as a hollow chamber into which compressed air or other motive fluid is admitted through an orifice 40. This orifice 90 is screw-threaded so as to receive a screwed union of a hose or other conduit through which the driving fluid is conducted to the machine. In the lower end of the cylinder 32 there is an aperture 41 by which the cylinder 32 is maintained always in open 95 communication with the interior of the air chamber in the pedestal 10.

An outlet conduit 42 from the chamber leads through a port 43 into the cylinder 44 of a reciprocating piston control valve 45. The latter comprises a valve stem having two enlarged cylindrical portions 46 and 47 which make a substantially air tight sliding fit in the cylinder 44.

A conduit 48 leading to the upper end of the cylinder 12 communicates with the valve cylinder 44 through a port 49 and a conduit

50 leading to the upper end of the lower cylinder 11 also communicates with the valve cylinder 44 through a port 51.

Another port 52 opening into the cylinder 44 communicates with a screw-threaded orifice 53 adapted to receive a hose or other conduit connection leading to the cylinder 61 of the dolly hammer 62.

There is also a port 54 opening into the cylinder 44 and communicating with an exhaust orifice 55.

The end of the valve spindle is formed as a rack which is engaged by a toothed segment 56 mounted on a rock shaft 57 which can be rocked about its axis by means of a handle 58.

It will be seen therefore that by movement of the handle 58 the valve 45 can be moved to three control positions. In the position illustrated motive fluid is admitted through the conduit 42 and ports 43 and 49 to the conduit 48 and thence to the upper end of the cylinder 12. This will have the effect of moving the movable jaw downwardly on to the fixed jaw to impart a sharp blow to the bit or other work to be operated upon. During the admission of motive fluid to the piston 12, that is to say in the position of the valve as illustrated, the exhaust port 54 is closed off from the conduit 48 but is opened to the cylinder 61 of the dolly hammer 62 through the port 52. Also the conduit 54 communicating with the lower cylinder 11 is closed. By moving the handle 58 in such a manner as to return the valve 45 towards the left to the end of its stroke the air admission port 43 will be closed and the port 49 will be opened to the exhaust port 51. The driving fluid is thereby released from the cylinder 12 and the return piston 31 then operates to raise the upper piston 14. Thus by rocking the control handle 58 backwards and forwards between the two positions just described the upper piston 14 or movable jaw can be reciprocated as rapidly as desired to impart a succession of blows to the work which is positioned in the lower fixed jaw.

When it is required to operate on the end face of the work by means of the dolly hammer 62, it is found desirable to hold the movable jaw on to the work with a relatively great pressure, and for this purpose the control handle is moved so that the enlarged portion 46 of the valve 45 opens not only the port 49 but also the port 51 to the admission port 43. Consequently driving fluid is admitted to both of the cylinders 11 and 12 so that both pistons 13 and 14 serve to force the jaws together. A still further movement of the control valve 45 in the same direction will open not only the ports 49 and 51 but also the port 52 to the port 43 thereby setting in operation the dolly hammer 62.

It will be seen therefore that by means of the control handle 58 the forging hammer or movable jaw piston can be reciprocated to impart a succession of blows to the work by alternately admitting driving fluid to, and releasing it from, the upper cylinder 12. Alternatively for heavier blows the handle can be rocked through a greater angle so as to admit the driving fluid to both cylinders 11 and 12 simultaneously. It will be further seen that the dolly hammer 62 is not, and cannot be, energized until driving fluid is admitted to both cylinders 11 and 12 whereby the work is gripped between the jaws with the required pressure.

As a detail of construction it will be seen that at the lower end of the pedestal 10 there is a removable inspection cover 60 by the removal of which access is obtained to the interior of the chamber in the pedestal 10.

Although a particular form of apparatus embodying the present invention has been described in detail, it is obvious that many modifications may be made in the construction of the parts without departing from the invention as defined in the claims.

We claim:

1. A forging machine of the character described, comprising in combination two opposed work-holding jaws, one at least of which is movable relatively towards and away from the other, a single piston-rod connected with the movable jaw, two pistons and cylinders arranged in tandem, which pistons are both connected to said piston-rod and serve jointly to move said movable jaw towards the companion jaw, a driving-fluid supply conduit, three delivery conduits whereof one opens into one, the second opens into the other of said cylinders and the third is for connection to the cylinder of a reciprocating forging hammer arranged to operate on the work while it is held by said jaws, and control means for controlling the supply of driving-fluid from said supply conduit at will either to one of the two first-mentioned delivery conduits alone, or to both of the same simultaneously, or to all three said delivery conduits simultaneously.

2. A forging machine of the character described, comprising in combination two opposed work-holding jaws, one at least of which is movable relatively towards and away from the other, a single piston-rod connected with the movable jaw, two pistons and cylinders arranged in tandem, which pistons are both connected to said piston-rod and serve jointly to move said movable jaw towards the companion jaw, a driving-fluid supply conduit, three delivery conduits whereof one opens into one, the second opens into the other of said cylinders and the third is for connection to the cylinder of a reciprocating forging-hammer ar-

- ranged to operate on the work while it is held by said jaws, a three-position reciprocating valve for controlling the supply of driving-fluid from said supply conduit at 5 will either to one of the two first mentioned delivery-conduits alone or to both of the same simultaneously, or to all three said delivery-conduits simultaneously, and a rack-and-pinion device for operating said valve.
- 10 3. A forging machine of the character described, comprising in combination two opposed work-holding jaws, one at least of which is movable relatively towards and away from the other, a single piston-rod 15 connected with the movable jaw, two pistons and cylinders arranged in tandem, which pistons are both connected to said piston-rod and serve jointly to move said movable jaw towards the companion jaw, a 20 chamber to which driving-fluid can be supplied, which chamber constitutes a pedestal for supporting the machine, a third cylinder always in open communication with said chamber, a third piston carried by said piston-rod and movable in the said third cylinder, a driving-fluid supply conduit which 25 opens at one end into said chamber, three delivery-conduits whereof one opens into one and the other opens into the other of the two first mentioned cylinders, and the 30 third is for connection to the cylinder of a reciprocating forging-hammer arranged to operate on the work while it is held by said jaws, a three-position reciprocating piston-valve having a stem constituting a toothed rack for controlling the supply of driving-fluid from the other end of said supply-conduit at will either to one of the two first
- mentioned delivery-conduits alone, or to both of the same simultaneously, or to all 40 three said delivery-conduits simultaneously, a toothed segment meshing with said rack, and a handle for oscillating said segment.
4. A forging machine of the character described, comprising in combination two opposed work-holding jaws, one at least of which is movable relatively towards and away from the other, a single piston-rod 45 connected with the movable jaw, two pistons and cylinders arranged in tandem, which pistons are both connected to said piston-rod and serve jointly to move said movable jaw towards the companion jaw, a driving-fluid supply conduit, an exhaust port, three delivery conduits whereof one 50 opens into one, the second opens into the other of said cylinders and the third is for connection to the cylinder of a reciprocating forging hammer arranged to operate on the work while it is held by said jaws, and control means for controlling the supply of driving-fluid from said conduit at will 55 either to one of the two first mentioned delivery conduits alone, or to both of the same simultaneously or to all three said delivery conduits simultaneously, and for connecting one of the first-mentioned delivery conduits first to said supply conduit whilst shutting it off from the exhaust port and then to said exhaust port whilst shutting it off from the 60 supply conduit for reciprocating said piston-rod.
- 65 In testimony whereof we have signed our names to this specification.
